[57] CLAIM

The ornamental design for a console for video display
unit with extendable keyboard support, substantially as
shown and described.

DESCRIPTION

FIG. 1 is a perspective view of a console for video display
unit with extendable keyboard support showing
my new design;

FIG. 2 is a perspective view with keyboard support in
extended condition;

FIG. 3 is a top plan view thereof;

FIG. 4 is a front elevational view thereof;

FIG. 5 is a right side elevational view thereof;

FIG. 6 is a rear elevational view thereof; and

FIG. 7 is a bottom plan view thereof.
